LASTING MACHINE

William Thomas Buckingham Roberts, Leicester, England, assignor to United Shoe Machinery Corporation, Flemington, N. J., a corporation of New Jersey

Original application February 23, 1943, Serial No. 476,828. Divided and this application February 14, 1944, Serial No. 522,243. In Great Britain February 28, 1942

8 Claims. (Cl. 12—14)

This invention relates to lasting machines, the present application being a division of another pending application Serial No. 476,828, filed on February 23, 1943. The invention is herein illustrated as applied to a power-operated toe-lasting machine of the same general character as disclosed in United States Letters Patent No. 2,134,148, granted on October 25, 1938, on an application of mine, but modified in certain respects as further disclosed particularly in Letters Patent No. 2,138,308, granted on November 29, 1938, and No. 2,140,652, granted on December 20, 1938, also on applications of mine. It is to be understood, however, that the invention is not thus limited in its applicability.

The machine to which the invention is herein shown as applied is provided with toe-embracing wipers having curved wiping edges for wiping the toe-end portion of an upper heightwise of a last and for thereafter wiping the margin of the upper inwardly over an insole on the last. Arranged to clamp the upper outspread on the wipers is a retarder which cooperates with the wipers to apply a pull to the upper as it is wiped heightwise of the last and thereafter controls the marginal portion of the upper as it is wiped inwardly over the insole. After the wipers have completed their inward wiping movements, they are partially retracted from over the shoe bottom and are then moved inwardly again to positions short of the limits of their first inward movements, whereupon a plurality of fastening-inserting devices are operated to drive a row of tacks beyond but near the edges of the wipers to fasten the upper in lasted position.

The above-mentioned fastening-inserting devices, consisting of a plurality of tackers, are so mounted as to permit them to swing individually in inward or outward directions transversely of the edge of the shoe bottom, and they are maintained in a properly grouped relation by plates having edges curved similarly to the wiping edges of the wipers and against which the devices are held by springs, the machine having means for imparting to these plates advancing and closing movements similar to corresponding movements of the wipers to bring the devices into proper positions for the insertion of the fastenings along the edges of the wipers. When the wipers are removed, as they sometimes are, to permit differently shaped wipers to be substituted for shoes of a different size or style, it is customary also to remove the plates which control the fastening-inserting devices and to substitute therefor differently

formed plates appropriate for the different wipers. Heretofore, upon such removal of the plates, the fastening-inserting devices released by the plates have been swung outwardly by their springs, and it has been a matter of considerable difficulty for the operator to return them to their properly grouped relation in mounting new plates in the machine. The present invention accordingly provides means for holding the fastening-inserting devices in their properly grouped relation when the means for controlling the devices is removed from the machine. As herein illustrated, the holding means comprises a flexible member controlled by levers which are movable to apply it about the group of devices preparatory to the removal of the controlling plates.

The invention further provides novel means for preventing portions of the wipers from being sprung heightwise of the shoe by the pressure of the upper thereon in the lasting operation. As herein illustrated, a substantially U-shaped device is arranged to cause the end faces of its two arms to engage the end portions of the wipers acting at the sides of the shoe bottom and thus to prevent them from being sprung as above described, the device being mounted for swinging movement out of operative position about an axis extending heightwise of the shoe to facilitate removal of the wipers from the machine. In order to insure that the above-described means for holding the fastening-inserting devices during the removal of their controlling plates will have been returned to a position such as not to interfere with the movements of the devices prior to the next operation of the machine, the construction herein shown is further such as to prevent the return of the U-shaped wiper-controlling device to its normal position unless the holding means has thus been returned.

The above and other features of the invention, including various novel details of construction and combinations of parts, will now be more particularly described with reference to the accompanying drawings and thereafter pointed out in the claims.

In the drawings,

Fig. 1 is mainly a plan view showing portions of the fastening-inserting devices or tackers of the illustrative machine and the means for controlling them, together with means provided by the present invention for holding the devices when the controlling means is removed;

Fig. 2 is a plan view of a portion of the struc-

ture shown in Fig. 1, with parts removed to show other parts more clearly;

Fig. 3 is a section on the line III—III of Fig. 2, with parts omitted;

Fig. 4 is a section on the line IV—IV of Fig. 2, with parts omitted;

Fig. 5 is a section on the line V—V of Fig. 1, with parts omitted;

Fig. 6 is a perspective front view showing particularly the wipers and the device for preventing their front end portions from being sprung heightwise of the shoe;

Fig. 7 is a plan view on an enlarged scale of certain parts shown in Fig. 6; and

Fig. 8 is a view, partly in right-hand side elevation and partly in section, showing the wipers and the fastening-inserting devices and other parts associated therewith as they appear substantially at the beginning of the wiping of the upper heightwise of the last by the wipers.

For wiping the toe end of the upper heightwise of the last and for thereafter wiping its margin inwardly over an insole on the last the machine is provided with a pair of wipers 2 (Figs. 6 and 8) having wiping edges curved to embrace the upper around the toe and operated by means fully disclosed in the above-mentioned Letters Patent No. 2,134,148. The shoe is positioned bottom upward for the toe-lasting operation and is clamped and held in that position between an insole-engaging hold-down 4 and a toe rest 6. Arranged to cooperate with the wipers is a retarder 8 which clamps the upper outspread on the wipers, as shown in Fig. 8, to apply a pull thereto as the upper is wiped heightwise of the last and continues to control the upper as the wipers are advanced and closed to wipe its marginal portion inwardly over the insole. Thereafter, following partial retractive movements and second inward movements of the wipers, a plurality of tackers 10 (Figs. 1 and 8) are moved into tack-inserting positions beyond but near the edges of the wipers and are operated to drive tacks to fasten the margin of the toe end of the upper in lasted position.

The machine further includes, as heretofore, a pair of tacker-controlling plates 12 for determining the positions of the several tackers 10 relatively to one another and to the edges of the wipers 2, these plates being generally similar to those identified by the reference character 283 in Letters Patent No. 2,134,148 but being provided with hooked ends 14 to assist in maintaining the tackers in proper assembled relation. The plates 12 are advanced bodily lengthwise of the shoe and are swung or closed inwardly widthwise of the shoe in time relation to corresponding movements of the wipers to cause the tackers to be properly grouped and positioned relatively to the edges of the wipers when the tacks are driven. As disclosed in the last-mentioned Letters Patent, the tackers are supported above the plates 12 for swinging movements in inward or outward directions transversely of the edge of the shoe bottom and are controlled by springs (not herein shown) which tend to swing them in outward directions and hold them against the inner edges of the plates 12 which are curved similarly to the wiping edges of the wipers. These plates are detachably supported on carrier plates 16 (Fig. 2), corresponding to the plates 290 of the last-mentioned Letters Patent, the carrier plates being mounted on a table 18 supported on the lower ends of parallel links 20, as also more fully disclosed in said Letters Patent. The carrier

plates 16 are provided with cam slots 22 in which lie rolls 24 mounted on pins 26 on the table 18 to guide the carrier plates and their tacker-controlling plates 12 in their closing and opening movements laterally of the shoe. Connected to the carrier plates are links 28 and connected to the table 18 are links 30, the links 28 and 30 corresponding respectively to the links 293 and 297 of the above-mentioned Letters Patent. It will be understood that through these links the advancing and closing movements are imparted to the plates 12 in proper time relation to the corresponding movements of the wipers.

For supporting the plates 12 on the carrier plates 16, the plates 12 are provided with arcuate tongues 32 (Figs. 3 and 4) arranged to fit in complementary recesses in the carrier plates. Additional supporting means for the plates 12 is afforded by L-shaped clips 34 which are secured to these plates and portions of which extend outwardly over the carrier plates 16. The plates 12 are held detachably in their proper positions on the carrier plates by pins 36 which extend through holes in the carrier plates into holes in the plates 12 (Fig. 4), these pins having heads 38 which overlie portions of the carrier plates. Bearing on the head of each pin is a leaf spring 40 a portion of which is clamped between the upper surface of the corresponding carrier plate and a member 42 secured to this plate. This arrangement permits the plates 12 to be readily removed when it is necessary to substitute differently shaped plates to correspond to differently shaped wipers to be used in the machine, since removal of the pins 36 leaves the plates 12 free to be detached from their carrier plates 16.

Removal of the plates 12 as above described would, unless prevented, free the tackers 10 to the action of their controlling springs, so that they would be swung individually in outward directions by the springs, and it would be a matter of considerable difficulty for the operator to swing them all inwardly again to their proper positions and to hold them in properly grouped relation during the insertion of a substitute pair of plates in the machine. For purposes of this invention the machine herein shown is accordingly provided with means for holding the tackers substantially in their normal grouped relation during removal of the plates 12 and the substitution of other plates. This means comprises a pair of curved levers 44 (Fig. 1) arranged in crossed relation to each other and mounted to swing respectively about different pins 46 supported by the table 18. Supported on rearwardly extending arms of the levers 44 are trunnion blocks 48 through which extends a transverse rod 50 having right and left screw threads engaging respectively the different trunnion blocks. Upon rotation of this rod, therefore, by a suitable knob (not shown) on its left-hand end the front end portions of the curved levers 44 are swung inwardly toward each other with components of forward movements toward the front of the machine. Pivotally mounted on a vertical pin 52 on the front end of each of the levers 44 is a plate-like member 54. Each member 54 is arranged to present a rearwardly and inwardly extending inner edge 56 and is further provided near its front end with a pair of downwardly extending lugs 58 spaced apart forwardly and rearwardly of the machine. Extending through the two pairs of lugs and secured to the forward lug of each pair are the opposite end portions of a flexible wire brace or loop 60. This wire brace

and the inner edges 56 of the plate-like members 54 are normally positioned a short distance away from the outer faces of the group of tackers 10, as shown in Fig. 1. When it is desired to remove the plates 12 the front ends of the levers 44 are swung inwardly and forwardly by turning the rod 50 in one direction, thereby wrapping the wire brace 60 about the group of tackers and bringing the edges 56 of the members 54 into contact with several of the tackers near the opposite ends of the group. Preferably, the levers 44 are thus moved far enough to separate the tackers slightly from the edges of the plates 12. Thereafter, when these plates are removed and while other plates are being substituted, the tackers are held in assembled relation and are prevented from springing outwardly. To afford better control for the members 54 when they are moved inwardly against the tackers, each of these members is provided at its rear end with an upwardly extending pin 62 arranged to engage the inner face of the lever 44 associated therewith.

For purposes also of the present invention, the machine herein shown is further provided with means for engaging the upper faces of the front end portions of the wipers 2 to prevent them from being sprung upwardly by the pressure of the upper materials thereon in the lasting operation, thus rendering them more effective to wipe the upper properly over the insole in locations near the ends of the tip seam, especially in operating on shoes having comparatively heavy upper materials. This means comprises an inverted U-shaped brace or bridge piece 64 (Figs. 6 and 7) pivotally mounted at its left-hand end on a vertical stud 66 corresponding to the left-hand stud identified by the reference character 123 in Letters Patent No. 2,134,148. At its right-hand end the bridge piece has a slot 68 (Fig. 7) extending into it from the rear to receive a second vertical stud 70 corresponding to the right-hand stud 123 of the above-mentioned Letters Patent, and mounted in the bridge piece is a spring-pressed detent 72 arranged to engage this stud to hold the bridge piece in operative position. The lower end faces of the vertical arms of the bridge piece are arranged to engage the top faces of the front end portions of the wipers as above described. Before removing the wipers and the corresponding tacker-controlling plates 12, when different wipers and plates are to be substituted, the operator swings the bridge piece 64 forwardly about the left-hand stud 66, the detent 72 yielding to permit this movement of the bridge piece. In order to insure that the wire brace 60 will have been returned to an idle position, where it will not interfere with the movements of the tackers, before the machine is next operated after substitute wipers and tacker-controlling plates have been inserted, the levers 44 controlling the wire brace are provided at their front ends with forwardly projecting lugs 74 (Fig. 1), and the bridge piece 64 is provided with rearwardly projecting lugs 76 (Fig. 7) which will engage the lugs 74 and prevent the bridge piece from being returned to its operative position if the levers 44 have not been moved by the turning of the rod 50 to return the wire brace.

The manner of use of the structure provided by the present invention having already been fully explained, no further description of the operation is necessary.

Having described the invention, what I claim as new and desire to secure by Letters Patent of the United States is:

1. In a lasting machine, the combination with wipers having wiping edges curved to embrace an end portion of an upper and movable to wipe the margin of the upper inwardly over an insole on a last, of a plurality of fastening-inserting devices for inserting fastenings in a row along the edges of the wipers to fasten the upper, controlling means for maintaining said fastening-inserting devices properly grouped relatively to the edges of the wipers, said controlling means being removable to permit differently formed means to be substituted when differently shaped wipers are used in the machine, and mechanism movable into position to hold said fastening-inserting devices in their grouped relation when said controlling means is removed and other such means substituted.

2. In a lasting machine, the combination with wipers having wiping edges curved to embrace an end portion of an upper and movable to wipe the margin of the upper inwardly over an insole on a last, of a plurality of fastening-inserting devices for inserting fastenings in a row along the edges of the wipers to fasten the upper, controlling members having faces curved similarly to the edges of the wipers for maintaining said fastening-inserting devices in properly grouped relation, said members being removable to permit members having differently curved faces to be substituted when differently shaped wipers are used in the machine, and means including a flexible member movable into position to embrace the group of fastening-inserting devices and to hold them in properly grouped relation when said controlling members are removed and other such members substituted.

3. In a lasting machine, the combination with wipers having wiping edges curved to embrace an end portion of an upper and movable to wipe the margin of the upper inwardly over an insole on a last, of a plurality of fastening-inserting devices for inserting fastenings in a row along the edges of the wipers to fasten the upper, controlling members having faces curved similarly to the edges of the wipers for maintaining said fastening-inserting devices in properly grouped relation, said members being removable to permit members having differently curved faces to be substituted when differently shaped wipers are used in the machine, a flexible member arranged to embrace the group of fastening-inserting devices and to hold them in properly grouped relation when said controlling members are removed and other such members substituted, and levers supporting said flexible member and movable to apply it to the group of fastening-inserting devices.

4. In a lasting machine, the combination with wipers movable to wipe the margin of an upper inwardly over an insole on a last around an end of the last, of a substantially U-shaped device so mounted as to cause the end faces of its two arms to engage end portions of the wipers acting at the sides of the shoe bottom to prevent said portions of the wipers from being sprung heightwise of the last by the pressure of the upper thereon.

5. In a lasting machine, the combination with wipers movable to wipe the margin of an upper inwardly over an insole on a last around an end of the last, of a device arranged to engage end portions of the wipers acting at the sides of the shoe bottom to prevent said portions of the wipers from being sprung heightwise of the last

by pressure of the upper thereon, said device being mounted for swinging movement out of operative position to facilitate removal of the wipers from the machine.

6. In a lasting machine, the combination with wipers movable to wipe the margin of an upper inwardly over an insole on a last around an end of the last, of a substantially U-shaped device so arranged as to cause the end faces of its two arms to engage end portions of the wipers acting at the sides of the shoe bottom to prevent said portions of the wipers from being sprung heightwise of the last by pressure of the upper thereon, said device being mounted for swinging movement out of operative position about an axis extending heightwise of the last to facilitate removal of the wipers from the machine.

7. In a lasting machine, the combination with wipers having wiping edges curved to embrace an end portion of an upper and movable to wipe the margin of the upper inwardly over an insole on a last, of a plurality of fastening-inserting devices for inserting fastenings in a row along the edges of the wipers to fasten the upper, controlling means for maintaining said fastening-inserting devices properly grouped relatively to the edges of the wipers, said controlling means being removable to permit differently formed means to be substituted when differently shaped wipers are used in the machine, mechanism movable into position to hold said fastening-inserting devices in their grouped relation when said controlling means is removed and other such means substituted, bracing means arranged to engage portions of the wipers to prevent them from being sprung heightwise of the last by the pressure of the upper thereon, said bracing means being

displaceable to facilitate removal of the wipers from the machine, and means for preventing return of said bracing means to its normal position unless said mechanism for holding the fastening-inserting devices has been moved away from said devices.

8. In a lasting machine, the combination with wipers having wiping edges curved to embrace an end portion of an upper and movable to wipe the margin of the upper inwardly over an insole on a last, of a plurality of fastening-inserting devices for inserting fastenings in a row along the edges of the wipers to fasten the upper, controlling means for maintaining said fastening-inserting devices properly grouped relatively to the edges of the wipers, said controlling means being removable to permit differently formed means to be substituted when differently shaped wipers are used in the machine, a flexible member arranged to embrace the group of fastening-inserting devices and to hold them in properly grouped relation when said controlling means is removed and other such means substituted, levers supporting said flexible member and movable to apply it to the group of fastening-inserting devices, and bracing means arranged to engage portions of the wipers to prevent them from being sprung heightwise of the last by the pressure of the upper thereon, said bracing means being
